UNITED STATES PATENT OFFICE

EDWIN NATANAEL BRODEN, OF ROXBURY, MASSACHUSETTS

CENTERING DEVICE FOR LATHES

Application filed January 9, 1930. Serial No. 419,667.

My invention relates to improvements in centering device for lathes and more especially for jewellers' lathes, and the objects of my improvements are, first, to provide a device to hold the spotter and, second, a device for lifting the spotter away from the work during operation of drilling.

I attain these objects by the mechanism illustrated in the accompanying drawings, in 10 which—

Fig. 1 is a side view of my centering device shown in position for centering or spotting the work.

Fig. 2 is a side view showing my centering 15 device with the spotter arm raised and out of the way of the work.

Fig. 3 is a plan view of Fig. 1.

Fig. 4 is a front view of the spotter arm, showing the spotter affixed to same.

20 Fig. 5 is a side view of the spotter arm showing the slot for spring adjustment.

Fig. 6 is a side view of the spotter.

Similar numerals refer to similar parts throughout the several views.

25 1 is the tail stock of a lathe carrying a slide-able spindle, 2 is the spindle attached to drill chuck 3, 3¹ is the drill. On the end of spindle 2 is loosely pivoted a lever 4, to one end of said lever 4 is a loosely pivoted arm 5, this arm is pivotally connected to a projec- 30 tion 6 on tail stock.

On the top of tail stock or spindle carrier is attached a latch or catch 7, this latch is supported and held in place by an arm 8, at- 35 tached to the spindle carrier, on the front end of latch 7 and on top is a hook 9.

The underside is a cutaway portion 10, this cutaway portion 10 forms a projection. This 40 latch 7 is loosely pivoted at 11, and on the rear end of latch 7, is an outwardly turned

projection 12. On the arm 8 is also a pro- 45 jection 13, this projection has a screw at- tachment 14 which regulates the movement of the arm 7. On arm 7 is affixed a spring 15, one arm attached to arm 7, and the other end attached to a projection 15¹ on the tail stock 1. This spring 15 holds the arm 7

in position. On the spindle 2, and rigidly attached to the rear of drill chuck is an arm 16, on this arm 16 is fastened an angle iron 50

17, the front end of which acts as a support for the spotter arm 18. This spotter arm is slotted at 19 to allow movement of said arm 18. This movement is controlled by a spring 20, which surrounds spotter arm 18.

55 On this slotted spotter arm 18 is a pivot 21, this pivot extends on each side of said arm, the inner end to hold spring 20 in place, and the outward end runs through a slot 22 on an arm 23 which is pivoted to arm 16, and on one

end of this arm is a projecting piece 24. 25 is the head of spotter arm 18, the head holds the spotter 26 in place by a set screw 27. 28

is the work clutch and 29 the work to be drilled. In operating my centering device, 60 it is moved forward as in Fig. 1. This shows in position ready to be spotted or centered.

The spotter arm 18 is then moved back by lever 4 until the projection 24 on arm 23 comes in contact with the cutaway portion 70

10 on arm 7. This operation throws the spotter arm up as in Fig. 2 of the drawings and away from the work which is now ready to be drilled. To release spotter arm and

bring it down to position for spotting or cen- 75 tering, this device is moved back by lever 4 until the projection 24 on arm 23 comes in contact with catch 9 which releases the spotter arm. The projection 24 after the arm is

lifted stays under the shoulder 10 until the 80 spindle is moved towards the left. The arm 18 cannot go down because the projection 24 on arm 18 does not catch on to the hook 9 on the front end of latch 7 until the next back- 85

ward movement to the right, when the hook 9 is dropped down, a slot 11 in latch 7 allows it to drop. In Fig. 2 the projection 24 on arm 18 is not on the same level as in Fig. 1, it is raised up, that is the reason the arm 18 is up.

90 The projection 24 on arm 18 hooks onto the hook 9 if moved to the right.

Heretofore the spotter 26 was placed on and also taken off the work to be spotted by hand.

95 Having now fully described my invention, what I claim is:—

In a device of the class described, a tail stock support, a tail stock spindle slidably mounted therein, means for sliding said spin- 100

dle, a chuck at one end of said spindle, an angle piece near the other end of spindle, a latch loosely pivoted to said angle pieces, a spring for urging said latch in one direction, an angle piece near the forward end of the spindle adjacent to the chuck and having a transverse pivot, a spotter arm having a longitudinal slot mounted on said pivot, a lever pivotally mounted on the angle piece and having a longitudinal slot at its forward end and a rearwardly projecting portion having a catch to be engaged by the latch when the spindle is moved rearwardly, a perforated plate slidably mounted on the spotter arm and having a pin to engage the slot in the lever and a spring interposed between said plate and the second mentioned angle piece.

EDWIN NATANAEL BRODEN.
